(57) **CLAIM**

The ornamental design for a folding ladder as shown and described.

DESCRIPTION

The patent or application file contains at least one drawing executed in color. Copies of this patent or patent application publication with color drawing(s) will be provided by the Office upon request and payment of the necessary fee.

1. Folding ladder

FIG. 1.1 is a left side view of the folding ladder, shown in a fully open position, illustrating my new design;

FIG. 1.2 is a front and left side perspective view thereof, shown in a fully open position;

FIG. 1.3 is a right side view thereof, shown in a closed and folded position;

FIG. 1.4 is a rear perspective view thereof, shown in a closed and folded position;

FIG. 1.5 is a rear view thereof, shown in a fully open position;

FIG. 1.6 is a right side view thereof, shown in a partially open position;

FIG. 1.7 is a front and right side perspective view thereof, shown in a partially open position;

FIG. 1.8 is an enlarged inside view of the upper portion of the left side of the ladder, shown in a fully open position;

FIG. 1.9 is a front view thereof, shown in a fully open position; and,

FIG. 1.10 is an enlarged right side view of the upper portion of the ladder, shown in a fully open position.

(Continued)

The broken lines depict the boundaries of the partial enlargements and form no part of the claimed design.
